UNITED STATES PATENT OFFICE.

CHRISTIAN WILLIAM VILHELM MESSERSCHMIDT, OF COPENHAGEN, DENMARK.

METAL CAPSULE FOR BOTTLES.

1,100,440.

Specification of Letters Patent. Patented June 16, 1914.

Application filed January 17, 1912. Serial No. 671,735.

To all whom it may concern:

Be it known that I, CHRISTIAN WILLIAM VILHELM MESSERSCHMIDT, a subject of the King of Denmark, residing at Copenhagen, Denmark, have invented new and useful Improvements in Metal Capsules for Bottles, of which the following is a specification.

This invention relates to improvements in soft metal caps for bottles particularly those which are provided with one or more tongues which serve the purpose of pulling off the cap. It has been found in practice that these tongues often do not completely serve the purpose of removing the cap but the tongue or some portion of the cap only is torn away. These tongues in the way they have hitherto been formed have other disadvantages more particularly that the presence of the tongues makes it difficult to automatically feed the caps through a machine for the purpose of bringing them into position for attachment to the bottles and in packing or handling the tongue or tongues are very liable to be torn off.

My invention relates to an improved method of constructing the cap and tongue so as to strengthen the tongue at its point of juncture with the cap proper and thus obtain a line which will strengthen the tongue and serve to direct the tear into the cap when a sufficiently forcible pull is applied to the tongue. I provide this directing line by forming a laterally extending ridge in the metal at the part where the tongue projects from the edge of the cap. This ridge can be applied to a tongue of any shape or outline and the improved tearing quality thus obtained enables the tongue to be easily pulled with a sweeping movement which will entirely free the cap. This ridge may be formed in the course of forming the cap and tongue, but in practice it will preferably be formed by constructing the tongue in the usual manner and then, preferably at the time when the lining of cork or other material is lodged in the inside of the cap, bending up the tongue or tongues so that they lie as closely as is needed for the purpose against the body of the cap.

I have found that when the tongue of a soft metal cap has been so folded against the

body of the cap, the formation of the tear-directing ridge can be completed by the simple operation of unfolding the tongue, for it is well known that after a sheet of metal has been folded along one line it is difficult to unfold it along exactly the same line and the result of an attempt to unfold it is to create the crease or ridge herein referred to. The unfolding operation is so simple that it may be left to be performed by the ultimate user in the act of opening the sealed bottle. For this purpose he must open out the folded up tongue and in so doing he will complete the ridge. It will be found that a tongue provided with a reinforcing ridge at its line of joinder with the edge of the cap, will not be readily torn away when the tongue is grasped, and pulled for the purpose of removing the cap, but on the contrary the reinforcement will compel the cap to tear upwardly from one or both corners of the tongue and across the body of the cap, thereby releasing it from the bottle.

Other advantages are incidental to the employment of a bottle cap in my improved form, as for example, that with the tongues closely folded up they may be readily fed into an automatic capsuling machine and that bottles so capped can be packed and handled with less risk of accidental damage to the tongues.

In the accompanying drawing, Figure 1 is a side view of the top of a bottle provided with the improved sealing cap; and Fig. 2 is a similar view with parts broken away but taken at right angles to the view shown in Fig. 1.

Referring to the drawing by letter: *a* indicates the soft metal cap, of aluminum or other suitable metal, while *b* indicates the tongue integral with and depending from the edge of the flange of the cap.

b' indicates the annular groove in the cap formed by the capping tool in forcing the flange of the cap under the bead on the bottle. Along the horizontal line of joinder between the tongue *b* and the edge of the flange of the cap, there is formed, or to be formed, a ridge, the location of which is indicated in Fig. 1 by dotted lines *c'* and in Fig. 2 by the representation *c'* of the ridge

itself. This ridge may be formed by bending the tongue upward to the position indicated by the dotted lines *c* and then bending it back again to the position shown in full lines.

5 I claim—

A soft metal flanged cap for bottle sealing, provided with a tongue depending from the edge of the flange and having a rein-

forcing ridge along its line of joinder with 10 the flange for the purpose set forth.

In witness whereof, I subscribe my signature, in the presence of two witnesses.

CHRISTIAN WILLIAM VILHELM MESSERSCHMIDT.
